PRECIPITATOR

Cyril C. Levy, Pittsburgh, Pa., assignor to Westinghouse Electric & Manufacturing Company, East Pittsburgh, Pa., a corporation of Pennsylvania

Application February 14, 1934, Serial No. 711,194

8 Claims. (Cl. 183—7)

The invention relates generally to systems for the precipitation of solid particles from gases and more particularly to the controlling of the current supplied for performing the precipitating process.

It has been found that when the charging circuits of the precipitating system are connected directly to a source of supply that the system does not readily re-establish normal precipitating conditions after a flashover. Expedients, such as connecting a resistor in series circuit relation with the charging system, have been resorted to, but this results in a considerable power loss.

The object of the invention is to provide for impressing a voltage on the ionizing electrode of a precipitation system with a small power loss during the normal ionizing process and for momentarily reducing the voltage impressed on the electrode when a flashover occurs to enable the system to re-establish normal operating conditions.

It is also an object of the invention to provide for utilizing changes in the voltage conditions at the electrode of a precipitation system for controlling the voltage impressed on the electrode.

Other objects of the invention will, in part, be obvious and, in part, appear hereinafter.

The invention accordingly is disclosed in the embodiment thereof shown in the accompanying drawing, and comprises the features of construction, combination of elements and arrangement of parts which will be exemplified in the system hereinafter set forth, and the scope of the application of which will be indicated in the claims.

For a fuller understanding of the nature and objects of the invention, reference may be had to the following detailed description taken in connection with the accompanying drawing, in which the figure is a diagrammatic view of a precipitation system arranged in accordance with this invention.

In order to reduce the smoke nuisance in the vicinity of large industries and in some instances to recover valuable products from smoke and gases, precipitation systems have been employed. In industries, such as the manufacture of iron and steel, the gases from blast furnaces are cleansed in order that they may be utilized for operating internal combustion engines.

Referring to the drawing, the reference character 10 designates generally a smoke stack or pipe through which gases containing solid particles are conveyed. As illustrated, the stack or pipe 10 is grounded at 11. The ground connec-

tion may be made in any suitable manner well known in the art.

A wire or electrode 12 is disposed in the pipe or stack 10 to receive a negative ionizing potential or voltage. The electrode 12, as illustrated, is connected to the plates of the rectifying tubes 13 and 14.

The negative potential for the electrode 12 may be drawn from any suitable source of power and in this instance a transformer 15 is provided. As shown, the transformer 15 is provided with secondary coils 16 and 17 which are connected to the filaments of the tubes 13 and 14, respectively. The filaments of the rectifier tubes 13 and 14 may be heated by transformers 36 and 37 respectively which in turn are connected to a suitable power source.

The primary winding 18 of the transformer 15 is supplied from a source of alternating current power 19, which in this instance is a transmission system.

In order to supply an alternating potential to the transformer 15 with a small loss of power, two three-electrode electronic tubes 20 and 21 are connected between the power source 19 and one terminal of the primary winding 18 of the transformer 15.

As illustrated, tertiary windings 22 and 23 are provided in the transformer 15 for impressing a voltage on the grids of the tubes 20 and 21 to control the flow of current. Interposed between the tertiary windings 22 and 23 and the grids of their corresponding tubes are variable resistors 24 and 25, respectively for changing as desired the voltage impressed on the grids.

In order to heat the filaments of the electronic tubes 20 and 21, small transformers 26 and 27 are provided. As shown, the primaries of these transformers are connected across the power source 19, while the secondaries are connected across the filaments.

A reactor 28 is connected in parallel circuit relation with the electronic tubes 20 and 21 to deliver current to one terminal of the primary winding of the transformer 15. The reactor 28 will be designed to meet the conditions existing in the particular system to which it is to be applied.

In the operation of the precipitation system when the ionizing process is being carried on normally the electrode 12 is charged through the rectifying tubes 13 and 14 at a predetermined voltage from the transformer 15. The voltage conditions in the transformer remain substantially constant as long as the charging operation continues without flashovers or short circuits.

As is well known in the operation of electronic tubes, the resistance offered to the flow of current may be controlled by the voltage impressed on the grid. In this instance, when a predetermined voltage is impressed on the electrode 12 the variable resistors 24 and 25 are adjusted to impress the proper voltage on the grids of the tubes 20 and 21, respectively, to permit current to flow through the tubes to one terminal of the transformer 15 with a minimum power loss.

When the voltage impressed on the electrode 12 stands at the predetermined value required for performing the precipitating process the transformer 15 is supplied with power from the power source 19 through the electronic tubes 20 and 21. The transformer circuit through the tube 20 extends from one side of the power source 19 through conductors 29 and 30, the plate and filament of the electronic tube 20, conductors 31 and 32, the primary coil 18 of the transformer 15 and conductor 33 to the other side of the power source. Power is supplied to the transformer for one-half of the cycle through this circuit.

Another transformer circuit connected in parallel circuit relation to the tube 20 extends from the energized conductor 29 through conductor 34, the filament and plate of the electronic tube 21, conductors 35 and 32 and the primary coil of the transformer 15 to the power source 19. This circuit provides for the supplying of current during the other half of the cycle. Thus, current is supplied continuously to the transformer 15 through the electronic tubes 20 and 21 from the alternating-current source 19 when the charging operation is proceeding normally.

Assuming that a flashover occurs at the electrode 12, then voltage conditions at the electrode 12 will vary greatly, causing a change in the voltage conditions in the transformer 15. In this manner the voltages impressed on the grids of the electronic tubes 20 and 21 are changed in response to variations in potential conditions at the electrode 12, with the result that the tubes offer high resistance to the flow of current. In fact, the electronic tubes may be so designed that they will act as valves and interrupt the flow of current through the supply circuits in which they are connected.

The supply of power through the electronic tubes 20 and 21 is interrupted on the occurrence of abnormal potential or voltage conditions at the electrode 12, but the transformer is still connected across the power source 19. The transformer circuit extends from the one side of the power source through conductor 29, reactor 28, conductor 32, the primary coil 18 of the transformer 15 and conductor 33 back to the power source.

When the electronic tubes 20 and 21 function to interrupt the supply of power through the circuits in which they are connected, the primary of the transformer 15 is connected across the power source through the reactor 28. The result is that the voltage drop across the reactor 28 momentarily greatly reduces the voltage applied across the primary of the transformer 15, and the voltage impressed on the electrode 12 is reduced to the point where it will not maintain an arc established by a flashover. As soon as the arc is interrupted, a deionizing process will take place at the surface of the electrode and normal voltage conditions will be established and the precipitating process will proceed.

From the foregoing it will be clear that there is a very small loss of power in the system dur-

ing normal operations but upon the occurrence of abnormal voltage conditions the flow of current is restricted until normal voltage conditions at the ionizing electrode are re-established. In this manner high efficiency and simplicity in operation are obtained.

Since certain changes may be made in the above system, and different embodiments of the invention could be made without departing from the scope thereof, it is intended that all matter contained in the above description or shown in the accompanying drawing shall be interpreted as illustrative and not in a limiting sense.

I claim as my invention:

1. A precipitation system comprising, in combination, an electrode, means for impressing a unidirectional potential on the electrode, means responsive to predetermined voltage conditions at the electrode for conducting current to the potential impressing means, and means independent of the voltage conditions at the electrode for controlling the voltage impressed on the electrode, said independent means being capable of limiting the flow of current.

2. A precipitation system comprising, in combination, an electrode, a source of power, means connected to the source of power for impressing a potential on the electrode to carry on a process of precipitation, means interposed between the source of power and the means for impressing a potential on the electrode for conducting current, said current conducting means being responsive to the voltage conditions at the electrode, and means for conducting current from the source of power to the means for impressing a potential on the electrode, said last mentioned conducting means being non-responsive to the voltage conditions at the electrode and capable of momentarily greatly reducing the voltage impressed on the electrode.

3. A precipitation system comprising, in combination, an electrode, a source of power, means connected to the source of power for impressing a potential on the electrode to carry on a process of precipitation, means interposed between the source of power and the means for impressing a potential on the electrode for conducting current, said conducting means being responsive to the voltage conditions at the electrode, and means for conducting current from the source of power to the means for impressing a potential on the electrode, said conducting means being non-responsive to the voltage conditions at the electrode and capable of momentarily greatly reducing the voltage impressed on the electrode, the current conducting means responsive to the voltage conditions at the electrode and the current conducting means not responsive to the voltage conditions at the electrode connected in parallel circuit relation.

4. A precipitation system comprising, in combination, an electrode, a source of power, means connected to the source of power for impressing a voltage on the electrode to perform the precipitating process, the means for impressing the voltage on the electrode being connected to the source of power through a plurality of parallel circuits, means responsive to voltage conditions at the electrode connected into some of the circuits for controlling the flow of current, and means not responsive to the voltage conditions at the electrode connected into the other parallel connected circuits, said non-responsive means being capable of greatly reducing momentarily the voltage impressed upon the electrode.

5. A precipitation system comprising, in combination, an electrode, a source of power, means connected to the source of power for impressing a voltage on the electrode to perform the precipitating process, the means for impressing the voltage on the electrode being connected to the source of power through a plurality of parallel circuits, means responsive to voltage conditions at the electrode connected into a plurality of the 10 circuits for controlling the flow of current, and means not responsive to the voltage conditions at the electrode connected into the other parallel connected circuits, said non-responsive means being capable of greatly reducing momentarily the 15 voltage impressed upon the electrode, the means connected in the parallel circuits being disposed to conduct current with small loss when precipitating voltages are impressed on the electrode and to greatly reduce the voltage impressed on the 20 electrode when a flashover occurs.

6. A precipitation system comprising, in combination, an electrode, means for impressing a voltage on the electrode to perform a precipitating process, a source of power for supplying the 25 voltage impressing means, conducting circuits connected between the source of power and the charging means, said conducting circuits being responsive to the voltage conditions at the electrode to offer small resistance to the flow of 30 current when the voltage impressed upon the electrode is that required for normal precipitating operation and for greatly reducing momentarily the voltage impressed on the electrode when a flashover occurs.

7. A precipitation system comprising, in combination, an electrode, means for impressing a voltage on the electrode to perform a precipitating process, a source of power for supplying power to the means for impressing a voltage on the electrode, a low resistance voltage controlled conducting circuit interposed between the source of power and the means for impressing a voltage on the electrode, the conductance of the circuit being controlled by the voltage at the electrode, and 10 a reactance connected in parallel circuit relation with the low resistance circuit, said reactance being non-responsive to the voltage conditions at the electrode and capable of greatly reducing momentarily the voltage impressed upon the electrode 15 when the flashover occurs disturbing the voltage conditions at the electrode and effecting the low resistance circuits.

8. A precipitating system comprising, in combination, an electrode, means for impressing the 20 voltage on the electrode to perform a precipitating process, a source of power for supplying the means for impressing a voltage on the electrode, means interposed between the source of power and the means for impressing a voltage on the electrode responsive to the voltage conditions at the electrode for delivering current with a low power loss when the voltage conditions at the electrode are suitable for precipitation operation 25 and for momentarily reducing the voltage impressed on the electrode when a flashover occurs. 30
